UNITED STATES PATENT OFFICE.

ERNEST DAVID LIPMANN, OF PARIS, FRANCE.

LUMINOUS DIAL.

1,017,896.

Specification of Letters Patent. Patented Feb. 20, 1912.

Application filed December 7, 1910. Serial No. 596,974.

To all whom it may concern:

Be it known that I, ERNEST DAVID LIPMANN, a citizen of the Republic of France, residing at 96 Boulevard Sébastopol, Paris, France, have invented certain new and useful Improvements in Luminous Dials, of which the following is a specification.

This invention relates to improvements in self illuminating devices and is especially adapted for application to time pieces for illumination of the characters on the dials thereof.

One of the objects of my invention is to provide a device having a maximum illuminating efficiency with a minimum use of illuminating material.

To this end, the invention embraces a construction wherein the characters to be illuminated are formed by openings in a front member or dial, which openings are shaped to conform to the characters to be exposed, the illuminating material being disposed on a rear member or dial and shaped to conform to the contours of the openings forming the characters in the front member or dial.

In the drawings:—Figure 1 illustrates a front dial or member embodying one form of my invention. Fig. 2, illustrates a rear member or dial adapted for use in connection with the dial in Fig. 1. Fig. 3 illustrates a modified form.

Like characters of reference designate similar parts throughout the different figures of the drawing.

A front member, indicated by 1, is illustrated in the form of a dial having openings 2, outlining the characters to be exposed. In the form shown the characters are 12, 1, 2, 3. In the rear of said front dial or member 1, a rear member or dial 3 is adapted to be disposed and a said rear dial or member 3 is provided with characters formed of a self-illuminating substance, of any desired ingredient, indicated at 4. The characters 4 on the dial 3 are adapted to be disposed in registry with the openings 2 of the dial 1, and as they conform to the openings

of the dial 1, the characters of the latter are illuminated in a manner to render it easy to 50 read the time of day.

It will be readily seen that the amount of self illuminating substance necessary in my improved construction, is reduced to a minimum while the efficiency and brilliancy of 55 the disclosure of the characters is in no way impaired. If desired, the characters in the dial 1 can be edged with any suitable color of paint so as to render the characters more easily visible in daylight.

In accordance with the form shown in Fig. 3, the characters 5, on the front dial 6, are formed by a series of perforations disposed in a manner to conform to the outline of the characters to be disclosed. This form 65 is particularly advantageous for facilitating the reading of time by daylight, as the juxtaposition of the perforations forming each letter, serves to greatly strengthen the effectiveness of the outlines of such letters or 70 characters. The rear member 3, may be used in connection with the dial 6, in the manner hereinbefore described.

I claim:—

1. In a self-illuminating device, the combination with a front member provided with an opening outlining a character, and an element in the rear of the opening of said member and provided with a self-illuminating substance shaped to conform to the 75 contour of the opening in said member and disposed in registry with said opening.

2. In a self-illuminating device, the combination with a front member provided with an opening, and a rear member or element provided with a self-illuminating substance shaped to conform to the character to be disclosed and disposed in registry with 80 said opening.

In testimony whereof I affix my signature 90 in presence of two witnesses.

ERNEST DAVID LIPMANN.
